175,985

UNIVERSAL WORK BENCH CLAMP

Joseph E. Sawyer, Gardena, Calif.

Application January 24, 1955, Serial No. 34,177

Term of patent 14 years

(Cl. D54—13)

The single figure is a perspective view of a universal work bench clamp showing my new design.

I claim:

The ornamental design for a universal work bench clamp, as shown.

References Cited in the file of this patent

UNITED STATES PATENTS

D. 454,553	Whitten	June 23, 1891
2,366,350	Ostling	Jan. 2, 1945
2,636,527	Schiemann	Apr. 28, 1953